UNITED STATES PATENT OFFICE.

FOLGER ADAM, OF JOLIET, ILLINOIS, ASSIGNOR TO CROWN IRON WORKS CO., A CORPORATION OF MINNESOTA.

JAIL-DOOR-LOCKING APPARATUS.

1,034,672.

Specification of Letters Patent. Patented Aug. 6, 1912.

Application filed July 17, 1911. Serial No. 638,820.

To all whom it may concern:

Be it known that I, FOLGER ADAM, a citizen of the United States, residing at Joliet, in the county of Will and State of Illinois, 5 have invented a new and useful Improvement in Jail-Door-Locking Apparatus, of which the following is a specification.

My invention relates to improvements in jail door locking apparatus and its principal 10 object is to provide means for controlling the opening, closing and locking of a series of doors, individually and collectively, from a single lever box.

In penal institutions it is of the greatest 15 importance to simplify the operation of the doors and to concentrate their control within in the reach of a single operator who can tell at a glance the exact condition of each door of the series, in this way preventing the 20 positioning or locking of a single door from being overlooked, and also fixing the responsibility for the condition of the doors.

The door action which my device is 25 designed to control in cell doors is as follows, to positively lock and unlock all doors of a series in their closed position, to positively lock and unlock any door of a series while maintaining the remaining doors locked, to lock and unlock any and all doors in their 30 wide open position, and to open and close any or all doors.

A further object of my invention is to 35 simplify the locking and operating mechanism of a series of jail doors reducing it to a single gang shaft controlled by a single locking lever to lock and unlock the doors of the series individually at pleasure, and a single operating bar actuated by an operating lever to control the movement of each 40 or all of the doors.

In the drawings with which I have illustrated 45 my device and which form part of this specification, I have illustrated the application of my invention to a series of two cell doors.

In these drawings Figure 1 is a front elevation 50 of the cells partly broken away illustrating the locking mechanism with both doors locked closed and the locking lever in its first position; Fig. 2 is a front elevation of the cells illustrating the operation of either door with the locking lever in its corresponding second and third positions; Fig. 3 is an elevation showing both doors unlocked and open, the locking lever being in

its fourth position; Fig. 4 is a section on the line X—X of Fig. 2 showing the operation of the locking bar and gang lock; Fig. 5 is an elevation of the lever box showing the locking and operating levers; Fig. 6 is a section on the line Y—Y, of Fig. 2; Fig. 7 is a section on the line Z—Z, Fig. 1; Fig. 8 is a view of the locking bar and cam strap; Figs. 9, 10, 11 and 12 show the different positions of the pairs of cams upon the gang 65 shaft at the two doors illustrated in the different positions of the locking lever.

In the above drawings I have illustrated a series of cell fronts provided with two sliding cell doors A and B. At the top of 70 the doors a mechanism box C extends across the front of the cells and contains the operating and locking mechanism. At the end of the series of cells is a lever box D containing the levers controlling the locking 75 and operating mechanism.

Each of the doors A and B is formed in the ordinary manner of a grating 2 fitted to close the cell front in one position and supported by grooved wheels 3 on a suitable 80 track 4 within the mechanism box C. The wheels 3 are journaled on an angle 5 which extends along the top of the door and underneath the track 4 carrying the door in its normal position. The bottom of the door 85 is guided by a stop angle 6 extending across the front of the cell.

One side of the cell door-way is provided 90 with a jamb piece 7 against which the door closes which has apertures 8 fitted to receive suitable locking members 9 carried by the front edge of the door. The locking members 9 are in the form of lugs having locking notches 10 on their upper sides which lie 95 within the door jamb 7 in the closed position of the door. Within the door jamb 7 is a guard 11 which is fixed to the walls of the cell and is spaced from the door jamb by sleeves 12 upon the bolts 13 which connect the guard and door jamb allowing the entrance of the lugs 9 through the apertures 8. Between the door jamb and guard lies the locking bar 14 which has slotted apertures 15 to permit the sliding movement of the bar upon the bolts 13 and apertures 16 to receive each of the locking lugs 9. The locking bar 14 in its lowest position engages the notches 10 of the locking lugs when the door 100 is in its closed position, securely locking the door in that position. The locking bar 14 110

extends upward into the mechanism box C and terminates in a cam strap 20 connected with the locking mechanism.

The operation of the locking bars is secured through a gang cam shaft 21 which extends across the series of cells within the mechanism box C. The shaft 21 is supported by suitable bearings 22 connected to the walls 23 of the mechanism box and terminates within the lever box D in a pinion 24 which is keyed to the shaft. A rack 25 sliding vertically within the lever box co-operates with the pinion 24 to rotate the gang shaft 21 and is operated through the rack bar 26 by the locking lever 27 which is pivoted on a quadrant 28 fixed to the wall of the lever bar. The gang shaft 21 passes through the cam strap 20 of the locking bars 14 and at each door carries a cam collar 30 operating within the cam strap 20. The cam collar 30 carries lugs 31 differently positioned at each of the doors to operate the locking bar of the different doors individually as desired at different positions of the gang shaft.

The cam strap 20 has two operating faces 32 and 33 on its inner side positioned vertically above each other in the line of movement of the locking bar. The operating face 32 as shown has the form of an inwardly extending lug which co-operates with a lug 31 to raise the bar 14 to its unlocking position. The lower face 33 is adapted to co-operate with a lug 31 on the cam shaft 21 to lock the bar 14 down in a position engaging the locking notches 10 in the lugs 9 of the doors A and B. Having a cam strap 20 that can be moved up or held down to unlock or positively lock the cell doors by means of lugs on the cam collar 30, I position the lugs on the cam collars at the different doors in such a manner that in successive rotative positions of the gang shaft the different individual doors are successively unlocked while the remaining doors remain locked and all the doors may be simultaneously locked and unlocked in two other positions of the shaft.

The different rotative positions of the gang shaft secured through locking lever 27 are shown in Figs. 1, 2 and 3 where the lever 27 is shown engaging successively notches 35, 36, 37 and 38 in the quadrant 28 and the corresponding positions of the cam lugs on the two doors are shown respectively in Figs. 9, 10, 11 and 12.

The cam strap 39 is connected with the locking bar 14 at the door A and the cam strap 40 is connected with the bar 14 at the door B. Cam collars 41 and 42 operating in the straps 39 and 40 carry lugs 43, 44 and 45. The lugs 43, 44 and 45 are so positioned on the cam collars that when any of the lugs is in contact with either of the cam faces of a strap none of the other lugs

are in contact with the other face of the cam strap. In Fig. 9 the lugs 44 on both collars are in the locking down position and both bars 14 are held in locking position. The corresponding position of the locking lever 27 is shown in Fig. 1. By moving the lever to the full line position shown in Fig. 2 the gang shaft is rotated to the position shown in Fig. 10 engaging notch 36 on the quadrant 28. At the door A the lug 43 has come into contact with the face 32 raising the strap 39 and unlocking the door A. To unlock the door B instead of the door A, the locking lever 27 must be moved to the dotted position shown in Fig. 2, engaging the notch 37 of the quadrant and throwing the gang shaft 21 into the position shown in Fig. 11. The lug 43 at the door B raises the strap 40 and its attached bar 14 unlocking the door B while door A is held locked by lug 45 on the collar 39. By moving the lever 27 into engagement with the notch 38 as shown in Fig. 3 lugs 44 at both doors are brought into contact with the faces 32 on straps 39 and 40 unlocking both doors A and B at the same time. The corresponding position of the unlocking cams is shown in Fig. 12.

It is evident that the number of doors which may be locked and unlocked by a single gang shaft may be increased indefinitely the essential feature being a series of cam lugs positioned on the gang shaft adjacent to the different doors to unlock their respective lock bars in successive positions of the gang bar and other cam lugs adapted to maintain the locked position of the lock bar of each door except when unlocked by its respective opening lug.

In connection with the locking mechanism and controlled by it is a door operating mechanism by means of which the doors of a series may be operated individually or collectively. The operating mechanism consists of an operating bar 46 lying in the mechanism box C and extending above the series of doors. The bar 46 is supported by a series of supports 47 on which are journaled anti-friction wheels 48 between which the bar 46 slides. At its extremity the bar is connected to the wall of the lever box C by a lazy tongs 49 and reciprocated longitudinally by an operating lever 50 fulcrumed within the lever box and connected to the lazy tongs by a link 51.

At the top of each door a support 52 is attached to the angle 5 and carries a sliding catch 53 connected thereto by bolts 54 and adapted to slide vertically. At its upper end the catch 53 is formed with projecting points 55 embracing the sides of the operating bar. An aperture 56 is provided within the catch adapted to receive a catch bar 57 pivoted within the mechanism box and slide on it. The catch bar 57 is pivoted at one side of the door-way and extends

through an aperture 58 in the cam strap 20 and along the top of the door through the aperture 56 in the catch when the door is in its wide open position. The catch 53 during the movement of the door slides along the catch bar 57 and is adapted to be raised or lowered by any movement of the catch bar which is itself moved about its pivot point by any motion of the cam strap.

10 The lower edge of the operating bar is formed with notches 59 so positioned that with the doors in their closed position and the operating bar in its closed position they correspond to the catches 53 on the different doors which may be raised to engage the notches whereby the longitudinal movement of the doors is controlled by the operating bar 46 and operating lever 50.

15 It will be readily understood that when the catch of any of the doors has been raised into engagement with the operating bar, the movement of the operating lever from the dotted position shown in Fig. 1 to the position shown in Fig. 2 causing the longitudinal movement of the operating bar in the mechanism box will cause a corresponding movement of the connected door or doors to open them and a return movement will carry the door to its closed position. The connection of a door with the operating bar occurs only when the latch on that door is raised into engagement with the notch in the bar. This movement of the latch can occur only when the latch bar is raised by means of the 20 cam strap through which it passes, and this movement in turn is produced by the action of the cam lugs on the gang shaft 21.

25 The longitudinal movement of the gang operating shaft is limited by stops 60 and 61 attached to it which at the limits of movement impinge upon a pin 62 fixed in the path of movement of the stops. The action of the stops prevents the too great movement of the operating bar and a consequent straining of the catches which may be engaged with the notches of the bars.

30 Attached to the catch 53 is a lug 63 (see Figs. 2 and 7) having an extremity formed with a notch 64 which is adapted to engage a suitable pin 65 fixed in the path of the lug when carried by the moving door. The pin is so positioned that when the door has been opened wide by the operating bar it lies below the notch 64 in the lug 63 and the movement of the catch 53 which detaches the door from the operating bar while in its open position engages the notch 64 upon the pin 65 holding the door in its open position until the catch has again been raised.

35 60 In operating my device to open any one of the series of doors the locking lever 27 is moved to the notch in the quadrant 28 corresponding with that door and the door can then be opened by moving the operating lever 50. When the door has been opened

wide the locking lever 50 may be returned to its locking position thus locking the door in its open position.

35 In accordance with the patent statutes I have described the principles of operation of my invention together with the apparatus which I now consider to represent the best embodiment thereof but I desire to have it understood that the construction shown is only illustrative and that the invention can be carried out by other means and applied to uses other than those above set forth within the scope of the following claims.

40 Having described my invention, what I claim as new and desire to protect by Letters Patent is:—

45 1. A jail door locking mechanism, comprising, in combination, a door a locking member on said door, a reciprocating bar co-operating with said member to lock said door, a catch mounted on said door, an operating bar mounted in connection with said door and notched to engage said catch in one position thereof, a catch bar mounted on a fixed pivot and connected with said reciprocating bar to be rotated thereby during the unlocking and locking of said door and 50 slideable in the catch on said door to engage said catch in all positions of said door and move said catch into and out of engaging position relative to said operating bar, and means for operating said reciprocating bar to unlock said door, whereby said door is connected with said operating bar when unlocked.

55 2. A gang mechanism for jail doors, comprising, in combination, a series of doors, a locking member in connection with each of said doors and adapted to lock said door, a gang shaft having an operative connection with each of said locking members, means on said shaft to operate said locking members to lock and unlock said doors individually or simultaneously in different positions of said shaft, door operating means in connection with said series of doors and means in connection with each of said doors, operated by said locking member thereon to connect said door with said door operating means when unlocked.

60 3. A gang mechanism for jail doors, comprising, in combination, a series of doors, a locking member on each of said doors, a reciprocating locking bar in connection with each of said doors and adapted to engage said locking member to lock said door, a cam strap at the upper end of each of said bars, and a cam shaft in connection with the straps of all of said bars and having cams thereon co-operating with said straps to raise said bars separately in different positions of said shaft to unlock the individual doors of the series separately, and simultaneously hold in locking position all locking bars not raised by said cams.

4. A jail door locking mechanism, comprising, in combination, a series of doors, a locking member on each of said doors, a reciprocating locking bar in connection with 5 each of said doors and adapted to engage said locking member to lock each door, a cam strap at the upper end of each of said bars, a cam on said locking bar adapted to turn in said strap said cam strap having a 10 cam lug and said cam having a circular face and a plurality of lugs thereon adapted in the revolution of said cam to impinge against said cam strap lug and raise each of said reciprocating bars individually out of 15 engagement with said locking member, in

one position of said cam and to depress said bar in another position of said cam and an operating shaft on which said cams are mounted in position to actuate said reciprocating locking bars in series or separately 20 while the remaining locking bars are in locking connection with said locking members.

In testimony whereof, I have signed my name to this specification, in the presence of 25 two subscribing witnesses.

FOLGER ADAM.
